ECCENTRIC ADJUSTMENT FOR ROLL DRIVES

William Messinger, Philadelphia, Pa.

Application November 6, 1950, Serial No. 194,345

10 Claims. (Cl. 74—395)

1

The present invention relates to mechanism for driving rolls and for adjusting the positions thereof in directions at right angles to their axes. More particularly, the invention relates to mechanisms by means of which the rolls of printing machines, paper or coating machines and similar mechanisms may be positioned in variably adjustable positions with a high degree of accuracy and facility.

In mechanisms, such as printing machines and paper coating machines and the like, there is need for positioning the impression rolls and the back-up rolls adjustably so that they may be moved to and from their operating positions quickly and surely. It is essential in these mechanisms that the operating position of such rolls be accurately determined in order that the return movement to such positions may be facilitated.

In accordance with the present invention mechanism is provided by means of which rolls of the above character may be effectively driven. A further object of the invention is to provide mechanism by means of which the axes of such rolls may be adjusted to and from desired operating positions.

Yet another object of the invention is to provide mechanism by means of which rolls of the above character may be driven effectively and, at the same time, readily moved from their operating to their inoperative positions.

These and other objects of the invention are accomplished by means of an eccentric bearing mechanism and operating elements therefor in which the drive mechanism for the roll is carried with the member that is eccentrically adjusted and in order that the invention may be readily understood, it will now be described in connection with the accompanying drawings, wherein

Figure 1 is a view in end elevation, partly in section and with certain parts omitted, showing the manner in which the bearing adjustment of the present invention is accomplished;

Figure 2 is a view in longitudinal section, taken on the line 2—2 of Figure 1, and looking in the direction of the arrows; and

Figure 3 illustrates the manner in which the journal shaft of the roll shown partially in Figure 2 is journaled eccentrically remote from the end shown in Figure 2.

Referring more specifically to the above drawings, a roll 10 is illustrated as being mounted in side frame members 11 and 12. The roll may be the backup roll of a paper coating machine, the impression roll of a printing machine, or any roll which is to be driven and the position of which is to be adjusted in a direction transverse to its axis.

2

Carried within the side frame members 11 and 12 are concentric shells 13 and 14, respectively, which are suitably secured within cylindrical portions 15 and 16 by bearing caps 11a. Within shells 13 and 14 eccentric bearing members 17 and 18 are journaled by means of bearings 19 and 20. Journal shafts 21 and 22 are formed on the roll 10 at its opposite ends and are received within the respective eccentric bearing members 17 and 18, being journaled therein by bearings 23 and 24, respectively. If desired, thrust bearings 25 may be formed between the journal shafts 21 and 22, and the respective eccentric bearing members 17 and 18. A hollow extension 27 is formed on the end of one of the journal shafts (in the form of the invention illustrated, this being journal shaft 21), and a radial bearing 28 is carried within this hollow extension for a purpose presently to be described.

Each of the eccentric bearing members 17 and 18 is formed with an arm 29 (Figure 1) having a bifurcated extremity 30 which receives trunnions 31 carried by a push-pull rod 32 that is moved axially by an electric motor 33 mounted upon the frame members 11 and 12. A suitable connection is provided for transforming the rotary motion of the motor into an axial motion, this mechanism not being illustrated in detail as it involves no part of the present invention. For example, the mechanism could consist of a nut and screw thread structure, but the details thereof need not be illustrated.

The lower end of each rod 32 is formed with a threaded portion 34 which is slidably received in a stop lug 35 fixed to the adjacent frame members 11 and 12. Adjustable nuts 36 and 37 are threaded on the extremity 34, and upon opposite sides of the stop lug 35. The nuts 36 and 37 thus limit the axial or push-pull movement of the rods 32 and by means of the adjustment of the nuts, the extent of rotation of the eccentric members 17 and 18 may be effectively and accurately controlled. In this fashion, since the motors 33 are operated synchronously, the adjustment of both journal shafts 21 and 22 is accomplished simultaneously and to the desired extent.

In order that the roll 10 may be driven, the eccentric bearing member 17 is formed with a housing extension 38, the outer extremity of which is provided with a flange 39 to which an adapter housing 40 is secured, the adapter housing 40 serving to mount a motor frame 41 and also being formed with a supporting wall 42. The armature shaft 43 of the motor is journaled at one end in bearing 44 carried by the motor housing, and at the other end in a bearing 45 carried by a hub 46 formed on the supporting wall 42.

The right-hand extremity of the armature shaft 43 is provided with sun gear 47 which engages a plurality of planet pinions 48 that are journaled in a planet spider 49. The left-hand extremity of the planet spider is hollow to encompass the sun gear 47 and is journaled in a bearing 50 carried by the hub 46. The right-hand extremity of the planet spider 49 is journaled in the bearing 28 carried by the journal shaft 21, and the housing extension 38 is provided with a planetary ring gear 51 which is engaged by the planet pinions 48. By means of this structure, the planetary system, including the sun gear 47, planet pinions 48, and ring gear 51, provides a suitable gear reduction from the armature shaft 43, and a further reduction is provided by a second planetary system comprising a sun gear 52 driven by the planet spider 49 which sun gear engages a plurality of planet pinions 53 that also engage an outer ring gear 54 carried by the housing extension 38. The planet pinions 53 are journaled in a cylindrical planet spider 55 that is journaled in the housing extension 38 by bearing 56 and is secured to the end of the journal shaft 21, as illustrated at 57.

Suitable ventilating mechanism may be provided for the driving motor and conventional electric circuits and controls for controlling the operation of the drive motor within the motor housing 41. It will be observed that the foregoing mechanism provides a continued coaxial relationship between the journal shafts 21 and 22 and the drive mechanism therefor while, at the same time, provision is made for moving these elements bodily in a direction transverse to their axis.

While the invention has been described with specific reference to the accompanying drawings, it is not to be limited save as defined in the appended claims.

I claim:

1. Driving and bearing adjusting mechanism comprising a rotatable element and journal shaft thereon, a journal bearing for the shaft, an eccentric sleeve within which the bearing is mounted, a support in which the sleeve is journaled, drive mechanism secured to the sleeve, means to drive the rotatable element from the drive mechanism, and means acting between the support and the eccentric sleeve to turn the sleeve in its journal in the support.

2. Driving and bearing adjusting mechanism, according to claim 1, wherein the sleeve turning means comprises an element mounted on the support, an arm on the sleeve, a connecting rod, means to move the rod axially by the motor, and means to connect the rod to the arm.

3. Driving and bearing adjusting mechanism, according to claim 1, wherein the sleeve turning means comprises an electric motor on the support, an arm on the sleeve, a connecting rod, means to move the rod axially by the motor, and means to connect the rod to the arm.

4. Driving and bearing adjusting mechanism, according to claim 1, wherein the means to drive the rotatable element comprises an electric motor, means to mount the motor coaxially of the journal shaft, and means to drive the journal shaft by the motor.

5. Driving and bearing adjusting mechanism, according to claim 1, wherein the means to drive the rotatable element comprises a motor housing mounted on the sleeve, an electric motor having an armature journaled in the housing coaxially of the journal shaft, and a planetary gear drive

mechanism between the armature and the journal shaft.

6. Driving and bearing adjusting mechanism, according to claim 5, wherein the planetary gear drive comprises a spider and spider shaft journaled in the housing coaxially of the journal shaft, a sun gear on the armature, planet pinions journaled in the spider and driven by the sun gear, a ring gear on the housing engaged by the pinions, a second sun gear on the spider shaft, a hollow extension secured to the journal shaft, second planet pinions journaled in the hollow extension and driven by the second sun gear, a second ring gear on the housing engaged by the second pinions, and means connecting the journal shaft to the hollow extension.

7. Driving and bearing adjusting mechanism comprising a roll, journal shafts at the ends of the roll, a frame, eccentric sleeves journaled in the frame, means acting between the frame and the eccentric sleeves to adjust the eccentric sleeves with respect to the frame, bearings in the sleeves to receive the journal shaft, drive mechanism carried by one of the eccentric sleeves, and means to drive the adjacent journal shaft by the drive mechanism.

8. Driving and bearing adjusting mechanism, according to claim 7, wherein the drive mechanism comprises a motor housing secured to the sleeve, an armature shaft journaled in the housing coaxially of the journal shafts, and a planetary gear connection between the armature shaft and the adjacent journal shaft.

9. Driving and bearing adjusting mechanism, according to claim 7, wherein the drive mechanism comprises a motor housing secured to the sleeve, an armature shaft journaled in the housing coaxially of the journal shafts, and tandem planetary gear connections between the armature shaft and the adjacent journal shaft.

10. Driving and bearing adjusting mechanism, comprising a roll, journal shafts at the ends of the roll, a frame, eccentric sleeves journaled in the frame, means to adjust the eccentric sleeves with respect to the frame, bearings in the sleeves to receive the journal shafts, a housing extension secured to one of the sleeves, a motor housing secured to the housing extension, a supporting wall carried by the housing extension, an armature shaft journaled in the motor housing and wall coaxially of the journal shaft, a spider shaft journaled on the wall and in the adjacent journal shaft, a first sun gear on the armature shaft, first planet pinions on the spider shaft and engaged by the first sun gear, a first ring gear in the housing extension engaged by the first planet pinions, a second sun gear on the spider shaft, a hollow extension secured to the adjacent journal shaft, and carrying a plurality of second planet pinions engaged by the second sun gear, and a second ring gear on the housing extension and engaged by the second planet pinions.

WILLIAM MESSINGER.
